CLAIM

The ornamental design for a fluid processing chamber as shown and described.

DESCRIPTION

FIG. 1 is a top perspective view of a fluid processing chamber;

FIG. 2 is a top plan view thereof;

FIG. 3 is a bottom plan view thereof;

FIG. 4 is a front elevational view thereof;

FIG. 5 is a rear elevational view thereof;

FIG. 6 is a right elevational view thereof; and,

FIG. 7 is a left elevational view thereof.

The broken lines shown in the drawings illustrate portions of the article that form no part of the claimed design.
